(57) **CLAIM**

The ornamental design for a cue caddy, as shown and described.

DESCRIPTION

FIG. 1 is a perspective view of a cue caddy showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom view thereof; and,

FIG. 8 is a perspective view thereof, the broken line showing of the cue case is included for the purpose of illustrating and forms no part of the claimed design.
